UNITED STATES PATENT OFFICE.

ROSS L. REYNOLDS AND ALFRED D. McGRAW, OF FALL RIVER, MASSACHUSETTS.

SADDLE FOR THE TOP ROLLS OF SPINNING-FRAMES.

1,104,932.

Specification of Letters Patent.

Patented July 28, 1914.

Application filed March 4, 1911. Serial No. 612,313.

To all whom it may concern:

Be it known that we, Ross L. REYNOLDS and ALFRED D. McGRAW, both of Fall River, in the county of Bristol and Commonwealth 5 of Massachusetts, have invented an Improvement in Saddles for the Top Rolls of Spinning-Frames, of which the following description, in connection with the accompanying drawings, is a specification, like letters 10 on the drawings representing like parts.

This invention relates to saddles which are used in connection with stirrups to put weight on the top rolls of ring spinning frames. The proper operation of the said 15 rolls requires an additional weight to be put upon them beyond the weight of the rolls themselves. This is customarily done by a saddle resting on the rolls and carrying a stirrup which is drawn down by a weight. 20 The distance of the two front rolls from each other varies according to the kind of cotton in use; and it is necessary that the saddle should be so constructed as to keep the weight either on all three rolls, or on the 25 front and back rolls alone as the work requires.

In the annexed drawings Figure 1 is a top view of the top rolls and our improved saddle. Fig. 2 is a vertical sectional view of 30 the same showing the saddle so adjusted as to put weight on the middle roll. Fig. 3 a vertical sectional view showing the saddle so adjusted as to put no weight on the middle roll. Fig. 4 is a cross section on line x, v , 35 Fig. 1. Fig. 5 is a cross section on line w, z , Fig. 1. Fig. 6 is a vertical sectional view of an alternative construction of the slide. Fig. 7 is a top view of said last named construction. Figs. 8 and 9 are views of the 40 slide and stirrup on line $x' y'$ showing how the stirrup is retained by the slide. Fig. 10 is a sectional view of another construction; and Fig. 11 is a top view of said last named construction.

The saddle is composed of two principal pieces, viz: the front saddle E having the bearing e for the front roll I, i , and the elongated shank G having the slot e' ; and the back saddle H having the curved bear- 45 ings h' and h adapted to engage the back roll, and the flat bearing h^2 adapted to engage the bearing j of the middle roll J when adjusted to put weight on the middle roll J.

On top of the front saddle the adjustable 50 slide A is mounted in the rabbeted guides a^2 . The slide itself is correspondingly rab-

beted as shown at e^4 . In the front portion of the slide is a transverse slot a in which is suspended the stirrup B. The slide A has the longitudinal slot a' through which passes the set screw C which is threaded into the front saddle and serves to retain the adjustment of the slide A. The under side of the shank G is rounded and is adapted to engage and slide in corresponding recesses 60 formed by projecting shoulders h^3, h^4 on the top of the back saddle H. The set screw F passes through the slot e' in the shank G and is threaded into the back saddle. It serves to retain the adjustment between the 70 front saddle and the back saddle. On the top of the front saddle is the oil well P, P' from which the oil holes p, p, p', p' , shown only on Figs. 6-11 lead to the front roll bearing. The oil well may if desired be 75 filled with felt or some other absorbent material.

Figs. 6 and 7 show an alternative construction of the slide. The slide A' is rounded, is slotted longitudinally and engages and 80 slides in the rounded recess a^4 in the top of the front-saddle, back of the oil well. It is provided with a circumferential groove A³. Within said groove the slide A' is elliptical in form, wider on its horizontal than on its 85 vertical diameter, the groove being of uneven depth. The hole in the stirrup B² is cut away at its lower edge, leaving an opening sufficiently wide to allow the grooved portion of the slide A' to enter said hole 90 when said slide is turned at right angles to its normal position. In other words the opening into said hole is slightly wider than the minor diameter of the elliptical portion of the slide A', and is less than the major 95 diameter of said elliptical portion. After the stirrup has been mounted on the slide, the slide is then turned into its usual position, Fig. 8, and the stirrup B' and the slide A' are thereby locked together. The 100 adjustment of the slide is retained by the set screw C.

A second alternative construction of the slide is shown in Fig. 10. In this construction there is the guide slide a^4 on the top of the front saddle E². The slide A² is slotted at its rear end A⁴, and is retained by the adjusting screw C². Toward the front of the stirrup-slide A² are a number of transverse slots on the underside. The stirrup 105 itself is, in this construction, suspended directly on the front saddle. The stirrup slide

A² is then engaged over the stirrup, and the engagement is retained by the set screw C².

Having thus described our said invention, we claim:

5. 1. A top-roll saddle consisting of a front-saddle having a straight elongated slotted shank adapted to engage the back-saddle on the under side of the front-saddle at two points, a back-saddle longitudinally adjustable with reference to the front-saddle and to the middle-roll, means to retain the longitudinal adjustment between the front-saddle and the back-saddle, a stirrup-carrier engaging the front-saddle, and a stirrup carried by the carrier.
10. 2. In a top roll saddle a front saddle having on the upper side a guide, a stirrup-slide slotted longitudinally and adapted to engage and slide on said guide, a portion of said stirrup-slide being wider horizontally than vertically and adapted to engage a corresponding recess in the stirrup, and a stirrup having a recess adapted to engage said
- 15.
- 20.

wider portion of the stirrup-slide, said recess being wider than the opening into it.

25

3. In a top-roll saddle, a front-saddle adapted to engage the back-saddle, a back-saddle, a stirrup-slide mounted on the front-saddle, a stirrup supported on said slide, and means to lock said stirrup and said slide together against vertical motion of the stirrup with respect to the slide.

30 4. In a top-roll saddle, a front-saddle adapted to engage the back-saddle at two points, a back-saddle, a stirrup-slide engaging the front-saddle and adapted to slide thereon, a stirrup engaging said slide, and means to fasten the stirrup and the slide together against vertical movement of the stirrup with respect to the slide.
